UNITED STATES PATENT OFFICE.

OLLOF ANDERSON, OF DEFIANCE, OHIO.

WASHING-MACHINE.

SPECIFICATION forming part of Letters Patent No. 463,850, dated November 24, 1891.

Application filed June 5, 1891. Serial No. 395,179. (No model.)

To all whom it may concern:

Be it known that I, OLLOF ANDERSON, a citizen of the United States, residing at Defiance, in the county of Defiance and State of Ohio, have invented certain new and useful 5 Improvements in Wash-Boards, of which the following is a specification, reference being had therein to the accompanying drawings.

This improvement relates more particularly 10 to that class of wash-boards which are provided with rubbing devices; and the invention consists in the peculiar construction, arrangement, and combinations of parts hereinafter more particularly described and then definitely claimed.

In the accompanying drawings, Figure 1 represents a plan of the wash-board with the guard turned down and part broken away. Fig. 2 is a vertical longitudinal section of the 20 same with the guard raised. Fig. 3 is a horizontal section through the line $x-x$ in Fig. 1. Fig. 4 is a plan of the acting face of the rubber detached.

Referring now to the details of the drawings by letter, A represents the sides, connected by cross-bars 1, 2, 3, and 4. Between 25 1 and 2 are set the zinc B and its backing C, which are secured to the sides in any convenient manner, but preferably by setting 30 the edges of the zinc and backing in suitable grooves. Attached to the lower side of the bars 3 and 4 is a thin board D, making a box E, in which may be set soap, &c.

Attached to the sides A are ribs F, through 35 which pass pins G, which act as pivots for a guard H, which normally occupies the position shown in Fig. 2. This guard has a notch h cut out of its bottom to receive a spring I, one of whose ends is attached to the guard 40 by staple and the other passes down through the bar 4, and the whole is so arranged as to have a tendency to keep the guard in a substantially vertical position, as shown in Fig. 2.

Resting on the sides A, between the ribs F, is the rubber J, comprising the side pieces 45 K, having anti-friction rollers k, which bear against the ribs F, a cross-piece L, covered with corrugated zinc or other suitable rubbing-surface, and a handle M. As a means of securing the zinc in place I may use the strips 50 l; but these are not absolutely necessary, as the zinc may be nailed directly to the cross-piece without the strips. To prevent wear and lessen friction I prefer to face the side pieces of the rubber with zinc k'. 55

By the above construction I have produced a very convenient washing apparatus, which can be made very cheaply, will cleanse the clothes rapidly with but little labor, will be very durable, and therefore not likely to get 60 out of order.

What I claim as new is—

1. The combination, with a wash-board having sides A and ribs F, secured to said sides, of the rubber J, having side pieces K, sliding 65 on said sides A, and provided with anti-friction rollers k, sliding against and between the ribs F, substantially as described.

2. The combination, with a wash-board having sides A and ribs secured to said sides, of the rubber J, having its side pieces K sheathed with metal k' on their bottom sides and resting on the tops of sides A, and provided with anti-friction rollers k, bearing against said ribs F, all substantially as described and 75 shown.

In testimony whereof I affix my signature, in presence of two witnesses, this 3d day of June, 1891.

OLLOF ANDERSON.
